**PROCESS FOR THE REDUCTION OF THE FREE
ACIDITY IN MINERAL LUBRICATING OILS**

George W. Ayers, Chicago, and William A. Kreuer, Ar-
lington Heights, Ill., assignors to The Pure Oil Com-
pany, Chicago, Ill., a corporation of Ohio

No Drawing. Filed Aug. 16, 1960, Ser. No. 49,829

1 Claim. (Cl. 208—263)

This invention relates to a method of reducing the content of acidic oxygenated compounds in hydrocarbon mixtures containing same, and, more particularly, to a process for the reduction of the acid neutralization number of mineral lubricating oils. More specifically, the invention relates to the discovery that heavy petroleum oils, such as solvent extracts obtained as by-products from the solvent refining of mineral lubricating oils, which solvent extracts may contain relatively high contents of naphthenic acids and related acidic materials, when heated with urea at a temperature of above about 400° F. and up to about 550° F., undergo a substantial reduction in acid neutralization number.

It is known that acidic oxygenated materials such as naphthenic acids can be neutralized and more or less extracted from various petroleum stocks, such as lubricating stocks, by treatment with various neutralizing agents and solvents. However, it is difficult, by these known processes to obtain products of reduced acid neutralization number which do not contain appreciable quantities of naphthenate salts. Such naphthenate salts in lubricants can be very troublesome during use of the lubricant. Sodium naphthenates tend to increase emulsification of the oil with water while ammonium naphthenates may, during use of the lubricant, cause deterioration of bearings, such as those of copper and lead. Ammonium naphthenates also tend to promote emulsification of the lubricant with water.

In accordance with the present invention, we have found that urea, used either in stoichiometric amounts or in excess of stoichiometric amounts, reacts with the naphthenic acids and other acidic materials in mineral lubricating oils to form stable amides which do not revert to any free acids during use or storage of the treated oil. Also, since any excess urea used in the reaction is insoluble in the oil, it settles out rapidly, and the treated oil can be decanted from the excess urea and used without further treatment. The naphthenic acids and other oxygenated materials are not removed from petroleum oils by the process of this invention, but are converted to substances having no free acidity, termed amides for the purposes of this invention. In addition, as part of the invention, we have found that the temperature is essentially critical; the reaction is slow at 400° F., and becomes rapid in the neighborhood of about 450° F., but at temperatures above 550° F. the decomposition of urea becomes rapid and competes with the amide-forming reaction.

Another feature of this invention is the discovery that by incorporating urea in mineral lubricating oils during their distillation, the products and the residue have low acid neutralization numbers.

Still another feature of the invention is the discovery that the unusual reduction in the acid neutralization number can be accomplished by contacting the oil with an adsorbent in the presence of urea at temperatures between about 400° F. and 550° F.

Accordingly, it becomes a primary object of this invention to provide a process for reducing the acid neutralization number of mineral lubricating oils.

Another object of this invention is to provide a process for reducing the acid neutralization number of mineral lubricating oils by treatment of the oil with urea.

2

Another object of this invention is to provide a process for reducing the acid neutralization number of mineral lubricating oils by treatment with urea at temperatures ranging from about 400° F. to 550° F.

Another object of this invention is to provide a process for reducing the acid neutralization number of solvent extracts by treatment with urea at temperatures ranging from 400° F. to 550° F.

In order to demonstrate the invention, the following examples are given:

EXAMPLE 1

A three-necked, 500-cc. glass flask was equipped with a mechanical stirrer, thermometer, and nitrogen-delivery tube. Into the flask was placed 300 cc. of extract oil (sample 5, Table I) from the production of 170 viscosity neutral. This extract oil had an acid neutralization number of 6.5, due to its content of naphthenic acids. A Glas-Col heating mantle was placed around the flask, and the oil in the flask was stirred mechanically under a blanket of nitrogen while the temperature was raised to 450° F. During a period of 4.2 hours, a total of 4 grams of urea was sifted into the hot oil at 15-minute intervals. At the end of this period, the acid neutralization number of the oil had dropped to 3.7. The excess of urea was insoluble in the oil and settled to the bottom of the flask after the stirring was discontinued.

EXAMPLE 2

30 A 100-cc. sample of the same extract oil as used in Example 1 was heated with 5 grams of urea at 450° F. without stirring, but under a blanket of nitrogen. At the end of 4 hours, the neutralization number of the oil was 5.2. A comparison of this result with that of Example 1 showed that the rapidity of reduction in acid neutralization number of the oil was closely dependent on intimate contact of the oil with the oil-insoluble urea.

EXAMPLE 3

40 A 300-cc. sample of the same extract oil as used in Example 1 was heated with urea under the same conditions except that the temperature was 400° F. instead of 450° F. At the end of 3 hours, the acid neutralization number of the oil was 6.3. A comparison of this result with that of Example 1 showed that the rate of reaction of urea with the naphthenic acids in the oil was very slow at 400° F., but was appreciable at 450° F.

The foregoing examples illustrate that the treatment with urea is successful in reducing the acid neutralization number to a low value. This reduction in acid neutralization number is considered to be unusually great because of the high acid number of the solvent extracts treated, and the peculiar nature of the naphthenic acids present in solvent extracts which the art recognizes as making them exceedingly difficult to remove or neutralize.

The following example is given to illustrate the distillation of an oil in the presence of urea.

EXAMPLE 4

60 A 400-cc. sample of aromatic extract oil (sample 5, Table I) from the production of 170 viscosity neutral oil, having an acid neutralization number of 6.5, is distilled under vacuum with four times the quantity of urea stoichiometrically required for the naphthenic acids present. The temperature is maintained above 450° F. during distillation. The distillate, representing 80% of the charge, has a drastically reduced neutralization number, less than 3. A similar distillation in the absence of urea produces an 80% distillate having essentially the same neutralization number as the charge.

In order to illustrate the advantages of treating an oil

with urea in the presence of an adsorbent, the following examples are given.

EXAMPLE 5

A three-necked, 500-cc. glass flask was equipped with a mechanical stirrer, nitrogen-delivery tube, and thermometer. Into the flask was placed 300 cc. of unfinished bright stock (sample 14, Table I) which had an acid neutralization number of 0.18. A Glas-Col heating mantle was placed around the flask, and the oil in the flask was stirred mechanically under a blanket of nitrogen while the temperature was raised to 450° F. Then a mixture of urea and Filtrol 60 clay, corresponding to 2.3 lbs. of urea and 6 lbs. of clay per barrel of the oil being treated, was added to the oil in the flask. The mixture was maintained at 450° F. for 30 minutes under a blanket of nitrogen, with constant mechanical agitation. Then the heating mantle was removed and the agitation continued until the oil in the flask had cooled to 200° F. The oil mixture was then filtered by suction through Celite filter aid. The filtered oil had a good odor and an acid neutralization number of only 0.05.

EXAMPLE 6

Another portion of the unfinished bright stock was treated in the same manner as in Example 5 except that the urea was omitted. The filtered oil obtained had a markedly inferior odor, as compared to the filtered oil from Example 5, and an acid neutralization number of 0.10.

Although the process of this invention is designed to destroy the free acidity of acidic oxygenated materials in hydrocarbon mixtures containing same, it is particularly applicable to the destruction of the free acidity of naphthenic acids in lubricating oils and fractions, including solvent extracts from the manufacture of both neutral oils and bright stocks. The naphthenic acids found in lubricating oil and fractions thereof are generally characterized as high-molecular-weight carboxylic acids,

Various types of hydrocarbon oil mixtures containing acidic oxygenated materials, including naphthenic acids, may be treated in accordance with this invention. Any hydrocarbon oil fraction which can be improved by a treatment which lowers the acid neutralization number is included as a material susceptible to treatment. Lubricating oil fractions, particularly neutral oils, bright stocks, and solvent extracts from the manufacture of neutral oils and bright stocks, can be advantageously treated in accordance with the instant process. The term "solvent extract" as used herein is intended to mean the extract product resulting from the treatment of lubricating oils and lubricating oil fractions with a selective solvent for the purpose of separating, in the extract phase, those materials which are predominantly aromatic in nature from the predominantly naphthenic and paraffinic materials which appear in the raffinate phase. Solvent extracts are produced as by-products from the solvent refining processes presently applied in the manufacture of modern lubricating oils. Various solvents are used for this purpose, including phenol, furfural, nitrobenzene, mixtures of sulfur dioxide and nitrobenzene, mixtures of phenol and water, and the well-known Duosol solvent. This latter solvent comprises a mixture of propane and cresylic acid. Since solvent extraction and the solvent extracts produced thereby are well known, there is no necessity for further description for purposes of this invention. It suffices to say that one skilled in the art may have reference to one or more of the United States patents which describe in greater detail the solvent extraction process and give the characteristics of solvent extracts that may be benefited by the process of this invention.

The following table gives the physical and chemical properties of several solvent extracts and lubricating oil fractions which are illustrative of the types of material that may be treated in accordance with this invention.

Table I.—Characteristics of Oils and Extracts That May Be Benefited by the Process of This Invention

A. LUBRICATING OIL EXTRACTS

Name	Sample No.	API Gravity	Flash (° F.)	Fire (° F.)	Saybolt Viscosity (sec.) at—		Acid Neutralization No.	Pour (° F.)
					100° F.	210° F.

C. NON SOLVENT REFINED OILS

Cylinder Stock A.G.	15	21.0	555	625	—	214	0.07	15
Black Oil	16	19.0	—	—	655	60	0.6	—

liquid and/or solid in physical state, containing mostly alicyclic or condensed alicyclic nuclei. These naphthenic acids show little or no unsaturation and consist essentially of acids boiling above about 600° F. Naphthenic acids falling within the foregoing definition are considered in the art to offer the greatest difficulties in removal from the hydrocarbon source.

The process of this invention may be carried out by any of the known methods of treating hydrocarbon mixtures with a solid or liquid treating agent provided the temperature of such treatment is maintained in the range of above about 400° F. to about 550° F. The process 70 may be carried out batchwise or continuously using any 75

of the various contacting apparatus available for this type of reaction.

Since the desired amide formation is always accompanied by some decomposition of the urea, it is preferable to use more than one to one molar ratio of urea to naphthenic acid. In practice, an amount of urea is used which is from one and one half to four times the quantity theoretically required to convert the naphthenic acids to amides. Any amount of urea may be used in practice, the upper limit being dictated by economic considerations.

The urea may be added to the oil in any convenient fashion, either before, during, or after the oil has been raised to the required temperature. It may be added in increments at definite time intervals, if desired. Since urea is a solid at ordinary temperatures and has a relatively low melting point, it may be sifted into the hot oil or it may be added as a liquid. In continuous operation the urea may be mechanically proportionated into the oil stream either in solid or liquid form.

For the best operation of this process, the oil is blanketed with an inert gas such as nitrogen, methane or natural gas to prevent atmospheric oxidation of the oil. Some provision must also be made for the gases liberated in the process. Ammonia is liberated during the reaction of amide formation and also from any concurrent decomposition of urea. In case water is present, carbon dioxide may also be liberated.

The time required for reaction of the urea with the oil at the process temperature is dependent upon the thoroughness of contact of the urea with the oil. Although the reaction is rapid at 450° F. and probably requires only a few minutes for completion, with only ordinary stirring of the urea with the oil several hours may be required.

In applying the process in a combined urea-clay treatment the ordinary clay-contacting processes known in the art may be employed. The type and amount of clay may be the same or approximately the same as in the ordinary type of operation when no urea is used. For example, an acid-treated clay may be used in amounts from 1 to 12 pounds per barrel of oil. The amount of urea may vary from 0.1 to 6 pounds per barrel oil with clay-treating conditions. The urea may be added to the oil in solid or molten form, before or during the clay contacting. Preferably a blanket of an inert gas, such as nitrogen, is used to prevent oxidation of the oil at the temperatures used, and agitation of the oil-urea-clay mixture is carried out during the total contact time which may vary from 20 minutes to 1 hour. A 30-minute contact time at 450° F. with an acid-treated clay such as Filtrol 60 gives very satisfactory results as indicated by Example 5. Examples of adsorbents that may be used are Riverside fuller's earth, natural Utah clay, alumina, bauxite, ball clay, china clay, montmorillonite and kieselguhr. The process may be applied during the distillation of lubricating oils. In the preparation of neutrals and bright stocks, particularly by vacuum distillation, most or all of the naphthenic acids and other oxygenated bodies can be converted into amides and related products, such as nitriles by mechanically proportioning urea into the oil during or before distillation. The solid or liquid urea may be added directly to the oil stream before it enters the fractionating tower. Urea may, if

desired, be added to the oil stream before it enters the furnace, or it may be added prior to entering the fractionating tower. The urea may be added in increments, one portion before the heater and another before the fractionating tower. Since under distillation conditions, some of the urea will undergo decomposition before amide or nitrile formation, the maximum effect is obtained by using an excess of urea over the stoichiometric requirements of the acids or other oxygenated compounds present in the oil. In ordinary operation of the process as a distillation, one and one-half to four times the stoichiometric amount of urea is used. The upper limit in the amount of urea used in the distillation technique is set by economic considerations. In actual commercial usage the amount of urea proportioned to the oil stream is determined by chemical analysis of the distillates and bottoms for neutralization number.

The distillation aspects of this invention are also applicable to the redistillation of oil such as a neutral, or bright stock, or a lubricating oil extract which contains an excessive amount of naphthenic acids or other oxygenated compounds. The operation applies to vacuum distillation with or without the use of steam or other inert gas. The process works best with the use of a minimum quantity of steam during the distillation.

The distillation, contacting and treating techniques and apparatus described in the following United States patents may be used in carrying out the instant process:

30	1,666,597	1,793,885	1,797,513	1,811,185
	1,894,323	1,897,389	1,930,597	2,679,471
	2,795,535	2,885,353	2,897,145	2,931,771

using the modifications herein described. Accordingly, the process of this invention comprises an improved method of reducing the neutralization number and/or odor of petroleum oils and related hydrocarbon mixtures by combined-urea-clay treatment, distillation in the presence of urea, or heating in the presence of urea, with or without the separation of the by-products herefrom, and under the conditions set forth. Although the invention has been explained by means of examples, these are merely illustrative and the only limitations attaching thereto appear in the appended claim.

The embodiments of the invention, in which an exclusive property or privilege is claimed, are defined as follows:

The method of reducing the acid neutralization number of hydrocarbons of the group consisting of bright stocks and solvent extracts obtained in the solvent refining of mineral lubricating oils which consists in distilling said hydrocarbons in the presence of urea at a temperature of about 400° to 550° F., and recovering distillates and residues having reduced acid neutralization numbers.
